DESIGN FOR COMBINATION TRACTOR AND TRAILER

Harold H. Robinson, Coral Gables, Fla., assignor
to Curtiss Aerocar Company, Inc., Coral Gables,
Fla., a corporation of Florida

Application March 16, 1934, Serial No. 51,080

Term of patent 14 years

To all whom it may concern:

Be it known that I, Harold H. Robinson, a citizen of the United States, residing at Coral Gables, in the county of Dade and State of Florida, have invented a new, original, and ornamental Design for Combination Tractor and Trailer, of which the following is a specification, reference being had to the accompanying drawing, forming a part thereof.

Referring to the drawing:

Fig. 1 is a top plan view of a combination tractor and trailer showing my new design;

Fig. 2 is a side elevation; and

Fig. 3 is a perspective view of the trailer portion of the combination.

Fig. 4 is a front elevational view of the trailer portion of the combination.

I claim:

The ornamental design for combination tractor and trailer as shown.

HAROLD H. ROBINSON.
